SOAP HOLDER

Edna T. Wilmington, Chicago, Ill.

Application June 30, 1953, Serial No. 364,997

1 Claim. (Cl. 45—28)

This invention relates to soap holders, and more specifically to the provision of a soap holding device so constructed and formed as to hold a cake of soap in such a manner as to permit almost the entire outside area thereof to be exposed to air for the purpose of drying it.

A problem of long standing to householders, and one for which many partial solutions have been proposed, arises because of the effect of water on a pressed cake of soap. It is well known that a cake of soap which is permitted to stand in water becomes soft and that the portion thereof which becomes soft is almost entirely wasted at the next instance of use of the cake of soap. This softening and wasting of the soap takes place both when the soap is permitted to lie in a wash basin and when it is situated in a receptacle which does not almost completely free the outside surface of the soap to the drying action of air.

It has become the practice to form devices, usually called soap dishes, with a grid or parallel ribs on the lower surface thereof to support a bar of soap above the bottom. Such devices are partially successful and tend somewhat to alleviate the problem of the cake of soap resting in a pool of water. However, these devices are not completely successful because they tend to entrap soap and water, and mixtures thereof, in such a fashion as to cause them to lose their effectiveness relatively rapidly. As soon as the soap and water mixture is accumulated to a height sufficient to touch the lower surface of the cake of soap as it is supported by the grid or ribs, the soap dish so formed has lost its usefulness.

It is therefore an object of this invention to provide a soap holder which will support a cake of soap in a manner which will free almost the entire outside surface of the cake of soap to the air for drying.

A further object is to provide a soap holder having attachment means associated therewith whereby the soap holder may be positioned on a wash stand or an adjacent wall surface, either removably or permanently.

Further objects and advantages in my invention will be apparent from a consideration of the following specification in connection with the accompanying drawings, in which:

Fig. 1 is a view in perspective of a soap holder formed in accordance with this invention.

Fig. 2 is a view in vertical section through the center line of the soap holder shown in Fig. 1, and detailing the construction of an attachment means.

Fig. 3 is a view in perspective of an attachment means similar to that shown in Fig. 2, and

Fig. 4 is a view in elevation and partially in section of a different embodiment of the invention shown in the other figures.

As particularly shown in Figs. 1, 2 and 3, the soap holder 10 comprises a base portion 11 preferably of flowing convex line, and terminating in an annular ring 12 at its base. The ring 12 should engage the surface upon which the soap holder is to be situated, and is of plain formation for ease of cleaning. It should be formed

2

of a resilient material so that it seals against the surface upon which the soap holder is mounted.

Above the base 11, and supported thereby, is a hump portion 13, shown of conical configuration although it can be of cylindrical formation. The hump portion 13 flows from the base 11 in a smooth curve, as at 14. It holds the soap high and dry, and provides space under the soap in which the user's hand may be inserted.

The upper end of the hump portion 13 is defined at the sloping shoulder 15 which merges into the base 16 of the pin 17 which has a projecting end 18. The pin 17 is shown in the drawings as being substantially vertical. However, it has been determined that it is not absolutely necessary to so position it, although it must extend above the horizontal from the shoulder 15 and the hump portion 13.

The soap 19 suggested in Fig. 2 is impaled substantially at its center on the pin 17. In constructions in which the base 11, the hump portion 13 and the pin 17 are formed of a strong material, it is not necessary to preform a hole in the cake of soap in order to impale it on the pin 17. However, in case the soap is especially dry and hard, and the material from which the soap holder 10 is formed is somewhat frangible, it may be found advisable to preform a small cavity in the surface of the cake of soap to receive the pin 17.

The suction cup 20 has a cup portion 21 of the usual hemispherical conformation, and is preferably formed of a suitable resilient material. Situated at the top of the cup 21 is a neck portion 22 which supports a head 23. A cavity 24 of a size adapted to receive the head 23 and the neck 22 is formed within and defined by the hump portion 13, and is situated for access from the rear side 25 of the base 11. Engagement of the suction cup 20 on a flat horizontal surface, such as found on wash basins, will removably position the soap holder 10 and increase its utility. With certain of the newer moldable materials, the base 11 and the cup 20 may be molded in one piece.

A slightly different embodiment of the invention is shown in Fig. 4. There, a suction cup 30 is shown holding a base 31 against a vertical side wall 32. The suction cup 30 is formed with an attachment means 33 adapted to mate with a cavity 34 formed in the base 31. Projecting substantially horizontally from the base 31 is the supporting arm 35 upon the outer end 36 of which is mounted a hump portion 37. The hump 37 terminates on its upper side in a shoulder 38 which merges with the base 39 of a pin 40 having an upper point 41. The soap 42 is similarly impaled upon the pin 40. This embodiment of the invention is useful in holding soap adjacent vertical side walls, such as in shower baths and around wash basins.

It is also contemplated that permanent attachment structure may be substituted for the suction cups, whereby the soap holder is permanently mounted in position on a plumbing fixture. A further variation contemplates a soap holder having a single base portion and a plurality of humps and pins whereby to hold several cakes of soap.

Having described my invention, what I claim as new and desire to protect by Letters Patent is:

A device for holding an imperforate soap bar, comprising a cup-shaped base having a cavity therein on one side and an annular rim, a soft resilient sealing ring mounted on said rim for engagement with a supporting surface, a soft resilient suction cup mounted on said base in said cavity and projecting outwardly therefrom beyond said ring for engagement with the supporting surface, said suction cup being smaller in volume than said cavity and thereby being wholly receivable therein when compressed to bring said sealing ring into engagement with the supporting surface, a sharply tapering pointed conical stud

on said base for directly impaling the imperforate soap bar, said stud being relatively short to prevent said stud from passing entirely through the soap bar, and a member of enlarged diameter on said base around the lower end of said stud forming a shoulder limiting penetration of 5 said stud into said soap bar.
